UNITED STATES PATENT OFFICE.

ANDREW J. ALLARD, OF RICHMOND, VIRGINIA, ASSIGNOR OF ONE-THIRD TO T. F. GREEN AND ONE-THIRD TO D. R. CREECY, JR., BOTH OF RICHMOND, VIRGINIA.

AIR-BRAKE-CONTROL-VALVE MECHANISM.

1,096,777.

Specification of Letters Patent. Patented May 12, 1914.

Application filed June 2, 1913. Serial No. 771,314.

To all whom it may concern:

Be it known that I, ANDREW J. ALLARD, of Richmond, in the county of Henrico and State of Virginia, have invented certain new 5 and useful Improvements in Air-Brake-Control-Valve Mechanism; and I do hereby declare the following to be a full, clear, and exact description of the invention, such as will enable others skilled in the art to which 10 it appertains to make and use the same.

This invention relates to improvements in air brake mechanism and more particularly to the controlling valve for the same, the object of the present invention being to so construct 15 such controlling valve that it may be operated automatically through the medium of electrically controlled means and accomplish the gradual application and release of the brakes.

20 With this and other objects in view, the invention consists in certain novel features of construction and combinations of parts as hereinafter set forth and pointed out in the claims.

25 In the accompanying drawings, Figure 1 is a vertical transverse sectional view of a valve mechanism embodying my improvements, and Fig. 2 is a similar view taken at right angles to Fig. 1.

30 My improvements are adaptable for use in electrical train control systems wherein the brake valve is controlled through the medium of instrumentalities along the road, for effecting the automatic control of the 35 brakes.

1 represents a valve casing and may comprise superimposed sections 2-3 suitably secured together. A compartment 4 is formed within the upper section 2 and located 40 within this compartment are electromagnets 5 to be electrically connected in circuit with suitable controlling means. These electrical connections do not however, constitute any part of my present invention 45 and a detail disclosure of the same herein is superfluous. An armature 6 is pivotally mounted in the compartment 4 and is held normally away from the poles of the magnets 5 by means of a spring 7. A duct 8 is formed in the lower portion of the upper casing section 2, and one end of this duct is connected by suitable coupling means 9 with a pipe 10 from a source of air under pressure, such as the usual compressed air reservoir. The other end of the duct 8 commu-

nicates with a vertical duct 11, the lower end of which latter communicates with a chamber 12 in the lower casing section 3. The lower end of the chamber 12 is connected, by means of suitable coupling devices 13 with the train pipe 14. Thus it will be seen that the air reservoir is connected with the train pipe by the ducts 8 and 11 and the chamber 12. A piston 15 is located in the lower section 3 of the casing and separates the chamber 12 from a superimposed chamber 16, said piston being provided with a stem 17 entering an exhaust pipe 18 which terminates within the chamber 12 and is provided with a port 19 communicating with said chamber,—the lower end of said rod being adapted to close said port and thus constitute an exhaust valve having a seat at 20. The stem or rod 17 of the piston 15 is provided with a small duct 21 communicating 25 at its lower end with the chamber 12 and at its upper end, with the chamber 16 above the piston,—said port being normally closed by a check valve 22. The chamber 16 above the piston communicates, through a port 23, with the duct 8, so that under normal conditions, pressures equal to train pipe pressure will be in the chambers 16 and 12 above and below the piston 15, and hence this piston 30 will be balanced and the exhaust port 19 kept closed.

A piston valve 24 is movable through a suitable opening connecting the duct 8 with the compartment 4 and is provided with suitable packing to prevent leakage of air 35 into said compartment, said piston valve being adapted, as hereinafter explained, to close the duct 8 and become seated in a manner to close the port 23. The piston valve 24 is provided with a stem 25 connected at 40 its upper end with an armature 6 so as to be operated by the movements of the latter.

The bottom wall of the upper section 2 of casing 1 is provided with a comparatively small duct 26 which communicates at its 45 lower end with the chamber 16 over its lower end with the chamber 16 over the piston 15, and with the upper end of this duct, a pipe 27 is connected and extends upwardly part-way through the compartment 4. At 50 its upper end, the pipe 27 is connected with a lateral pipe 28 extending through the wall of the casing and connected with one end of a pipe 29, the other end of the latter communicating with the exhaust pipe 18 and 55 110

this exhaust pipe is open to the atmosphere at 30. A valve 31 is located in the pipe 27 within the compartment 4 and the stem of this valve is connected, by means of a slot-
5 ted arm 32 with a suitable pin on the valve rod or stem 25.

It is apparent that when the ports are in the positions shown in the drawings, the 10 brakes will be released. Should the magnets 5 be energized, the armature 6 will descend and operate the piston valve 24 to close the duct 8 and the port 23. The downward movement of the rod or stem 25 of said piston valve will transmit motion 15 through the arm 32 to the valve 31 to open the latter. Communication between the compressed air reservoir and the train pipe is now closed, and the chamber 16 over the piston 15 is open to the exhaust through duct 20 26 and pipes 27, 28 and 29. Pressure in the chamber 16 is thus reduced and said piston unbalanced, so that the train pipe pressure in the chamber 12 will operate to raise said piston and open the exhaust port 17. The 25 train pipe pressure against the underside of the piston 15 will be gradually reduced by passage of air from this chamber through the small duct 21 to the chamber 16 and the escape of air from the latter will be some-
30 what restricted by the comparatively small duct 26, and for these reasons, the exhaust of air from the train pipe through the port 19 and the pipe 18 will be gradual, resulting in the gradual application of the brakes.
35 When the magnets are again de-energized, the piston valve will be raised to open the duct 8 and port 23, and the valve in the restricted exhaust of pipe 27 will be closed. Communication is now established between 40 the air reservoir and the train pipe and between the duct 8 and the chamber 16. Pressure thus admitted to the chamber 16 will operate to press upon the top of piston 15 and force the same downwardly to effect 45 the closing of exhaust port 19, but such movement of the piston will be gradual by reason of train pressure in the larger chamber 12 when said piston begins to move and until the pressure in the two chambers 12 50 and 16 become equalized. The brakes are now released.

Various slight changes might be made in the details of construction of my invention without departing from the spirit thereof or

limiting its scope and hence I do not wish to 55 restrict myself to the precise details herein set forth.

Having fully described my invention what I claim as new and desire to secure by Letters Patent, is:—

60

1. In a brake valve, the combination with a casing and a piston therein forming upper and lower chambers, of a restricted duct movable with the piston and connecting said chambers, a check valve for said duct, 65 an exhaust port communicating with the lower chamber and controlled by said piston, a main duct communicating with the lower chamber, means for connecting a source of compressed air with said main duct, means for connecting the lower chamber with a train pipe, a port connecting the upper chamber with the main duct, a main valve adapted to close the main duct and said port, a restricted exhaust passage communicating with said upper chamber and open to the atmosphere, and electro-magnetically operated means for controlling the operation of said main valve.

75

2. In a brake valve, the combination with 80 a casing and a piston therein forming upper and lower chambers, of a restricted duct movable with the piston and connecting said chambers, a check valve for said duct, an exhaust port communicating with the lower 85 chamber and controlled by said piston, a main duct communicating with the lower chamber, means for connecting a source of compressed air with said main duct, means for connecting the lower chamber with a train pipe, a port connecting the upper chamber with the main duct, a main valve adapted to close the main duct and said port, a restricted exhaust passage communicating with said upper chamber and open to the atmosphere, electro-magnetically operated means for controlling the operation of said main valve, a valve in said restricted exhaust passage, and connections between said valve and the main valve operating means. 95 100

In testimony whereof, I have signed this specification in the presence of two subscribing witnesses.

ANDREW J. ALLARD.
